Atty.

UNITED STATES PATENT OFFICE.

WILLIAM F. JENKINS, OF NEW ROCHELLE, NEW YORK, ASSIGNOR TO BAUER & BLACK,
OF CHICAGO, ILLINOIS, A CORPORATION OF ILLINOIS.

ATHLETIC SUPPORTER.

Application filed October 23, 1922. Serial No. 596,263.

To all whom it may concern:

Be it known that I, WILLIAM F. JENKINS, a citizen of the United States, residing at New Rochelle, in the county of Westchester 5 and State of New York, have invented certain new and useful Improvements in Athletic Supporters, of which the following is a specification.

The object of this invention is to prevent 10 the band of an athletic supporter from sagging and slipping down at the front which lessens the efficiency of the device for the purpose intended and permits the sack to slip through the legs to an uncomfortable 15 position.

A further object is to accomplish the desired results hereinbefore stated without adding materially to the cost of manufacture or to the structure of the supporter.

20 In the accompanying drawings I have illustrated a selected embodiment of the invention and referring thereto—

Fig. 1 is a perspective view of a supporter embodying the invention; and

25 Fig. 2 is a sectional view on the line 2—2 of Fig. 1.

Referring to the drawings, the supporter comprises a waist band 5 and leg bands 6, 6, which are usually and preferably made of 30 elastic webbing or equivalent material. The ends of the waist band may be overlapped and sewed together at the front thereof and covered with a facing strip 7.

The sack 8 is attached at its upper edge 35 to the front of the waist band adjacent the lower edge thereof, and is also attached by stitching or other suitable means at its lower end to the leg bands. The sack may be made of any suitable material but I prefer 40 to make it of a knitted fabric which will stretch to the form of a sack adapted for the purpose intended and I consider a knitted fabric having alternate rib stitch sections 9 and plain stitch sections 10 very 45 satisfactory material.

It has been the practice heretofore to sew the upper end of the sack to the waist band and cover it with a binding strip but experience has shown that supporters so constructed have a tendency to sag and slip 50 down at the front in actual use, and espe-

cially when worn by stout men, with the result that the desired supporting effect is materially lessened and the supporter works into an uncomfortable position on 55 the body and between the legs. I have found that this objectionable result can be avoided by employing an elastic binding strip 11 which is stitched to the waist band over the edge of the sack whereby the sack and the 60 elastic strip are secured to the waist band by the same stitching. It will be readily observed that if the binding strip is not elastic it will hold that part of the waist band to which it is attached rigidly and render it inelastic at the place where it is most 65 important that the waist band should cling snugly to the body for the pull on the waist band is primarily over that portion to which the sack is attached; but when an elastic 70 binding strip is used in accordance with my invention the elasticity of the waist band is maintained and availed of throughout its length and as well where the pouch is attached as at other parts so that the waist 75 band may cling snugly to the body at the front and stay in desired position. The elastic binding strip enables the waist band to better conform to the shape of the body of the wearer and enables the waist band to 80 support the pouch in the manner intended.

It is possible to vary the detail construction somewhat as may be required to adapt it for supporters of different kinds and for other reasons and it will be understood that 85 such changes may be made without departing from my invention provided they are within the scope of the following claims.

I claim:

1. An athletic supporter comprising an 90 elastic waist band, a sack fastened at its upper edge to the waist band, leg bands fastened to the waist band and to the lower end of the sack, and an elastic binding strip for fastening the sack to the waist band, said 95 binding strip being extensible in the same direction as the waist band.

2. An athletic supporter comprising an elastic waist band, a sack, leg bands connected to the waist band and to the sack, 100 and an elastic binding strip attached to the waist band over the upper edge of the sack

2
to fasten the sack and the strip to the waist band by the same stitching, said binding strip being extensible in the same direction as the waist band.

5 3. An athletic supporter comprising an elastic waist band, a laterally stretchable sack fastened at its upper edge to the front

of the waist band, leg bands fastened to the waist band and to the lower end of the sack, and an elastic binding strip for fastening the sack to the waist band, said binding being extensible in the same direction as the waist band. 10

WILLIAM F. JENKINS.
